US00D906655S

(12) **United States Design Patent** (10) Patent No.: **US D906,655 S**
Christensen et al. (45) Date of Patent: ** Jan. 5, 2021

(54) **SHOE**

(71) Applicant: **Reebok International Limited**, London (GB)

(72) Inventors: **Brian Christensen**, Centerville, MA (US); **Dennis Gaboriault**, Millbury, MA (US); **Paul Litchfield**, Westboro, MA (US); **Ricardo Vestuti**, Providence, RI (US)

(73) Assignee: **Reebok International Limited**, London (GB)

(**) Term: **15 Years**

(21) Appl. No.: **29/671,261**

(22) Filed: **Nov. 26, 2018**

Related U.S. Application Data

(60) Continuation of application No. 29/592,820, filed on Feb. 2, 2017, now Pat. No. Des. 838,452, which is a continuation of application No. 29/508,455, filed on Nov. 6, 2014, now Pat. No. Des. 779,179, which is a (Continued)

(57) **CLAIM**

The ornamental design for a shoe, as shown and described.

DESCRIPTION

FIG. 1 is a perspective view of a shoe showing the claimed design;

FIG. 2 is a right side view thereof;

FIG. 3 is a left side view thereof;

FIG. 4 is a top view thereof;

FIG. 5 is a bottom view thereof;

FIG. 6 is a front view; and,

FIG. 7 is a rear view.

The dashed broken lines in the figures show portions of the shoe that form no part of the claimed design.

The dot-dash broken lines in the figures show boundaries that form no part of the claimed design.

1 Claim, 6 Drawing Sheets

Related U.S. Application Data

division of application No. 29/416,615, filed on Mar. 23, 2012, now Pat. No. Des. 719,331.
